Term of patent 14 years

(Cl. D92—2)

Fig. 1.

Fig. 1.

Fig. 2.

FIG. 1 is a top plan view of a laminated absorbent underpad for bedding showing my new design;

FIG. 2 is an edge view of the underpad of FIG. 1;

FIG. 3 is a cross-sectional view of the underpad taken along line 3—3 of FIG. 1;

FIG. 4 is a view similar to FIG. 1 showing another embodiment of my design when a transparent cover sheet has been added;

FIG. 5 is an edge view of the underpad of FIG. 4; and

FIG. 6 is a cross-sectional view of the underpad taken along line 6—6 of FIG. 4.

The back of the pad is a conventional impervious sheet.

The essential features of my design reside in the particular pattern which is embossed upon the laminated absorbent underpad for bedding.

The present application is a continuation in part of

application Serial No. 66,684 filed September 11, 1961 and now abandoned.

I claim:

The ornamental design for a laminated absorbent underpad for bedding, substantially as shown and described.
